UNITED STATES PATENT OFFICE

2,566,867

AUTOMATIC REEL FOR GARDEN HOSE

Holless W. Allen, North Kansas City, Mo.

Application July 18, 1946, Serial No. 684,567

1 Claim. (Cl. 242—86)

2

1 This invention relates to structure for conveniently supporting a flexible conduit such as rubber hose and has for its primary object the provision of means for winding the hose upon a novelly formed drum that is specially supported so that the entire assembly may be revolved about a vertical axis as the hose is wound or unwound from said drum.

One of the primary aims of this invention is to provide a hose reel structure having as a part thereof, connection to a source of water supply so that the hose may always be maintained in connection therewith, yet may be moved to and from an operative position without disconnecting or manipulating any of the customary fixtures usually associated therewith.

A further aim of this invention is to provide means for supporting garden hose or the like, which means includes unique structure for connecting the hose to a source of fluid supply and having a reel mounted for rotation on a tubular member which serves both as a passageway for the fluid and as a means for automatically permitting swinging movement of the reel as the same is being rotated.

Other objects of this invention include the provision of hose reel structure that is exceptionally simple to construct, inexpensive to purchase and maintain in operative condition, strong and durable, not likely to get out of order and capable of being effectively positioned in any location convenient for use.

Other objects will appear during the course of the following specification, referring to the accompanying drawing, wherein:

Fig. 1 is a top plan view of a hose reel structure made to embody the present invention.

Fig. 2 is a side elevational view thereof.

Fig. 3 is a fragmentary, detailed view taken on line III—III of Fig. 1; and

Fig. 4 is a fragmentary, detailed view taken on line IV—IV of Fig. 2 with parts broken away to show the construction of connection between the arcuate tube and axle of the drum.

The drum for winding and supporting the hose 10 is broadly designated by the numeral 12 and has an axle 14 upon which the framework thereof is rotatably mounted. This axle 14 comprises one leg of a substantially U-shaped tubular member having a bight 16 and another leg 18.

In addition to the axle 14, the drum per se includes a pair of spaced-apart frames, each having a number of V-shaped sections 20. Bights 22 of each section 20 are looped around the axle 14 in side-by-side relationship as clearly shown

in Fig. 3. The legs of each section 20 extend radially from the axle 14 to present spokes for a wheel-like structure having a rim 24 fixed to the free ends of said legs of sections 20.

5 A cross-bar 26 interconnects the corresponding sections 20 of each frame by being fixed to each leg thereof respectively and it is upon these cross-bars that hose 10 is wound when the drum 12 is rotated about its axle 14.

10 The supporting means for the drum 12 consists of a tubular standard 28 within which a rod 30 is telescoped for free pivotal movement. It is contemplated that the standard 28 be held in an upright position by driving the same in the ground in any location desired. However, any means of support for standard 28 such as a platform or the like could be constructed without effecting the operation of this invention as disclosed in the drawing.

15 The rod 30 is flared outwardly as at 32 to present a shoulder for resting on the upper end of standard 28 as the rod 30 is rotated. The tubular leg 18 is welded or otherwise fixed to the rod 30 at a point substantially on a plane through the

20 longitudinal axis of the drum 12. The bight 16 of the U-shaped member of which legs 14 and 18 are a part extends outwardly and upwardly from its point of connection with the leg 18 and has a length sufficient to present a clearance between the rims 24 and the leg 18 as the drum 12 is rotated.

25 A conduit 34 is in communication with a source of fluid supply (not shown) and is attached to the free end of the leg 18 by means of the conventional fixture 36 obtainable on the open market.

30 The axle 14 extends outwardly beyond the frame having sections 20 as a part thereof remote from the bight portion 16 and an arcuate tube 38 is inserted therein.

35 The means of fastening the tube 38 to axle 14 is illustrated in Fig. 4. The bore through the axle 14 is enlarged near its open end to present a shoulder 40 against which one end of the tube 38 abuts. A second shoulder 42 nearer the open end of axle 14 is engaged by a gasket 44 circumscribing the tube 38. A metal ring 46 presses against the gasket 44 as a nut 48 in screw-threaded engagement with the axle 14 is manipulated. Thus,

40 the tube 38 is free to turn within the axle 14 and no leakage of fluid will exist at this point of connection.

45 The tube 38 terminates at a point between one

50 of the cross-bars 26 and the axle 14 and is con-

55 nected to the hose 10.

connected to the hose 10 by a fixture 50 similar to fixture 36.

In operation, the hose 10 is withdrawn from drum 12 by pulling the free end thereof and causing the drum 12 to rotate. As this action takes place and the operator moves to the point where the hose 10 is to be put in use, the entire reel structure will revolve within standard 28 through the medium of rod 30. Passage of fluid from conduit 34 is through leg 18, bight 16, axle 10 14, tube 38 and thence to the hose 10. Disconnection of fixture 36 permits the reel to be moved bodily with hose 10 wound thereon to a place of storage by the simple expedient of withdrawing the rod 30 from standard 28.

It is understood that hose reel structures having physical characteristics other than those shown in the accompanying drawings and herein described, might be made without departing from the spirit of the invention or scope of the appended claim.

Having thus described my invention, what I claim as new and desire to secure by Letters Patent is:

A garden hose reel comprising a shaft; a pair of spaced, parallel wheel-like members secured to the shaft, each member including an annular ring and a number of substantially V-shaped rods joining the ring and the shaft, the bight of said rods being rotatably looped around the shaft and the legs of the rods radiating outwardly from the shaft and having their free ends rigidly

joined to the ring; said ring and said rods being in a common plane; and a cross-bar interconnecting each leg respectively of one member with a corresponding leg of the other member intermediate the ends of the legs, the distance between each bar and the rings being the same, said rods being arranged to hold the rings concentric with respect to the shaft.

HOLLESS W. ALLEN.
